CLAIM

We claim the ornamental design for a light assembly, as shown and described.

DESCRIPTION

FIG. 1 a perspective view of a light assembly of the new design.

FIG. 2 is a back elevational view of the light assembly of FIG. 1.

FIG. 3 is a front elevational view of the light assembly of FIG. 1.

FIG. 4 is a side view of the light assembly of FIG. 1, which is a mirror image of the opposite side.

FIG. 5 is a top view of the light assembly of FIG. 1; and, FIG. 6 is a bottom view of the light assembly of FIG. 1. The dashed lines depict environmental aspects and form no part of the claimed design.
